(57) **CLAIM**

The ornamental design for a stick-and-shoot camera, as shown and described.

DESCRIPTION

FIG. 1 is a rear perspective view of a stick-and-shoot camera showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a rear perspective view thereof, showing the stick-and-shoot camera in an open position.

The broken lines depict portions of a stick-and-shoot camera in which the design is embodied and form no part of the claimed design.
